WILER & MOSS.

Gas Lighter.

No. 13,134.

Patented June 26, 1855.

INVENTORS

W. Wiler
Lucien Moss.

UNITED STATES PATENT OFFICE.

LUCIEN MOSS AND WILLIAM WILER, OF PHILADELPHIA, PENNSYLVANIA.

GAS-LIGHTER.

Specification of Letters Patent No. 13,134, dated June 26, 1855.

To all whom it may concern:

Be it known that we, LUCIEN MOSS and WILLIAM WILER, both of the city of Philadelphia, State of Pennsylvania, trading together under the firm-name of WILER & Moss, have jointly invented a new and Improved Mode of Turning On and Lighting Gas; and we do hereby declare that the following is a true, full, and exact description 10 of the same.

The nature of our invention consists in making a portable instrument for at the same time turning on gas; lighting gas, and carry matches, which avoids the use of oil, 15 spirits or fluid, of any kind, and dispenses with the necessity of filling, or any attention whatsoever. And we proceed to construct it as follows:

We take a tube A of brass or other metal 20 the edges of which are brought just so near together as will allow a catch of metal B to run easily between them.

The catch is made, in the shape and form shown in Figures C, D, on the drawings 25 hereto annexed, C being a sectional view, and D, a lateral view of the same, so that

the ends of the catch a a when placed inside the tube form a sort of forceps, which will hold a taper placed therein. This tube catch for holding the taper is then 30 inserted in a groove, cut on one side, at the end of a stick, or, rod E, of wood; or other substance. This forms the lighting part of the apparatus. A turner or wrench similar to Fig. F, of metal is then inserted 35 into the same end of the rod E, E, as the tube is; and a box of metal, G, or other substance incloses the other end of the rod to hold the matches.

We are aware that the taper, tube, and 40 turner have been heretofore separately used, and therefore we do not claim them.

What we claim and desire to secure by Letters Patent is—

The arrangement as herein described of 45 sliding spring catch taper and wrench with the holder for the purpose set forth.

LUCIEN MOSS.

WM. WILER.
